UNITED STATES PATENT OFFICE.

EDRIC C. WARREN, OF JOHNSTOWN, PENNSYLVANIA, ASSIGNOR TO
CENTURY STOVE & MANUFACTURING COMPANY, OF JOHNSTOWN,
PENNSYLVANIA, A CORPORATION OF PENNSYLVANIA.

DESIGN FOR A STOVE.

SPECIFICATION forming part of Design No. 36,161, dated December 9, 1902.

Application filed October 17, 1902. Serial No. 127,744. Term of patent 7 years.

To all whom it may concern:

Be it known that I, EDRIC C. WARREN, a citizen of the United States, residing at Johnstown, in the county of Cambria and State of Pennsylvania, have invented a new, original, and ornamental Design for Stoves, of which the following is a specification, reference being had to the accompanying drawings, forming part thereof.

10 Figure 1 is a front elevation of a stove, showing my new design. Fig. 2 is a side elevation of the same.

As shown in the drawings, the characteristic and leading features of my design consist 15 of a frame A, wider at the bottom or base in front and side elevation than at the top and having a curved or convex door B, of lattice

form, closing the front, having the ornamental scroll C extending across the lower part of the door and from the upper to the 20 lower edge thereof at the center, the curved top, the front, and sides of the frame being highly ornamented with interlacing scrolls D, as shown.

Having described my invention, what I 25 claim as new, and desire to secure by Letters Patent, is—

The ornamental design for a stove, as herein shown and described.

EDRIC C. WARREN.
